UNITED STATES PATENT OFFICE.

JOHN EDWARD SYKES, OF MANCHESTER, ENGLAND.

SEWING-MACHINE.

1,370,069.

Specification of Letters Patent.

Patented Mar. 1, 1921.

Application filed February 7, 1920. Serial No. 356,935.

To all whom it may concern:

Be it known that I, JOHN EDWARD SYKES, a subject of the King of England, residing at Manchester, in the Kingdom of England, have invented new and useful Improvements in and Relating to Sewing-Machines, of which the following is a specification.

This invention relates to a device for raising and lowering the presser foot and presser foot bar of sewing machines, and its object is to provide an improved device for this purpose and which is universally applicable to all types of sewing machines.

I attain this object by the mechanism hereinafter described with reference to the annexed drawing, wherein—

Figure 1 is a front elevation of a sewing machine provided with my improved device.

Fig. 2 is an enlarged end view of the head of the sewing machine.

Fig. 3 is an enlarged end view of details of the device.

Fig. 4 is an enlarged front view of a modification in construction of a part of the device.

Fig. 5 is a view in vertical section of another detail of the device.

Like letters refer to similar parts throughout the various figures.

Referring to Figs. 1 to 3 of the drawing, the presser foot bar B is embraced by a clip A which is secured against movement on the bar B by a set screw D. This clip may alternatively be provided on the presser foot C. To the clip A I secure one end of a flexible but inextensible member E, consisting for example of a number of wire strands twisted together in the form of a cable. The member E passes through a hole

in a bracket F secured to the head of the sewing machine by a screw P, and also extends through a tubular member G which is flexible but incompressible, consisting for example of closely coiled wire having a flexible covering, see Fig. 5. The one end of the member G bears against the bracket F which acts as an abutment and prevents downward movement of the member G. The member E is slideable in the member G

and both of them extend through the interior of the machine as indicated in Fig. 1 or along the exterior of the same and beneath the table, bench or the like supporting the sewing machine body to where a frame M is secured. The frame M carries a bracket J having a hole through which

an externally screw-threaded tube I passes. The tube I has two nuts A' and A² screwed onto it whereby its position in the bracket J can be adjusted and serves as an abutment for the other end of the member G which bears against an enlargement on the tube I, whereby longitudinal movement of the member G toward the bracket J is prevented. By adjustment of the nuts A' and B' the pressure on the member G can be regulated. The member E extends through the tube I and its other end is attached to a screw bolt K which passes through a lug provided on a lever L. The screw bolt K carries two nuts B' and B² whereby it can be adjusted to regulate the tension of the member E, and the lever L which may be in one or more pieces is pivotally mounted on the frame M at a point between its lower end and the end carrying said lug.

In operation when it is desired to raise the presser foot C, the operator pushes the lever L to the right and thereby draws the member E through the member G with the result that the end of the member E connected to the presser foot bar B by the bracket A draws the presser foot upward against the pressure of the compression spring provided on the presser foot bar B. When pressure on the lever L is released the presser foot is returned to its operative position by the action of the compression spring on the bar B, the lever L and the member E being thereby also returned to their initial positions.

The frame M may be attached to the machine, table, treadle or floor in an inverted, horizontal or inclined position, the members E and G being altered in length as to suit the different positions. In Fig. 4, the frame M is shown as attached to the floor and provided with a horizontal lever L. The other parts carried by the frame M are similar to those described with reference to Figs. 1 and 3, but their positions are altered to suit the changed position of the frame M. Downward pressure on the lever L pulls the member E and raises the presser foot and on release or upward movement of the lever L the member E returns to its initial position and the presser foot falls under the action of the compression spring on the presser foot bar B.

I claim:

1. Mechanism for raising and lowering

the presser foot of a sewing machine, comprising a flexible but non extensible member operatively connected at one end to the presser foot; a pivotal manually operable lever connected to the other end of said member; a flexible but incompressible member surrounding the first named member to guide said member; and fixed abutments against which the ends of the second named member abut, whereby movement of said lever in one direction pulls the first named member and thereby lifts the presser foot.

2. Mechanism for raising and lowering the presser foot of a sewing machine comprising an abutment on the sewing machine; a closely coiled wire forming a tube and abutting with one end against said abutment, said wire tube extending to beneath the sewing machine; a number of wires twisted to form a cable extending through and slidable in said wire tube, said cable being connected at one end to the presser foot; a tubular member abutting against one end of said wire tube and having one end of said cable passing through it; a fixed bracket carrying said tube; adjusting means on said tubular member for adjusting said tubular member relative to said bracket and forcing it against the end of said wire tube;

30 a fixed frame carrying said bracket; a

manually operable lever oscillatably mounted on said bracket, and an adjustable stud carried by said lever and connected to the other end of said cable, for the hereinbefore specified purpose.

3. Mechanism for raising and lowering the presser foot of a sewing machine comprising in combination, a clip attached to the presser foot bar; a compression spring on the presser foot bar tending to force the presser foot into operative position; a bracket attached to the sewing machine head; a stranded wire attached to said clip and passing through said bracket; a tube of closely coiled wire supported at one end by said bracket and containing said wire after it has passed through said bracket, said wire being slidable in said tube; a member which is stationary relative to said presser foot; a frame secured to said member; a bracket secured to said frame, a tubular member adjustable on said bracket and abutting against the other end of said tube, with said wire extending therethrough; a manually operable lever mounted on said frame; and an adjustable member mounted on said lever and secured to the other end of said wire; for the hereinbefore specified purpose.

JOHN EDWARD SYKES.
